(57) **CLAIM**

The ornamental design for a cover flap for confectionary product container, as shown and described.

DESCRIPTION

FIG. 1 is a front elevation view of the confectionary product container showing the cover flap, those portions of the confectionary product container shown in phantom are not part of the design sought to be patented and are provided for environmental purposes only;

FIG. 2 is a top plan view of the container;

FIG. 3 is a bottom plan view of the container;

FIG. 4 is a right side elevation view of the container;

FIG. 5 is a left side elevation view of the container;

FIG. 6 is a rear elevation view of the container;

FIG. 7 is a perspective view of the container;

FIG. 8 is a front elevation view of a second embodiment of the confectionary product container showing the cover flap, the second embodiment being a mirror image of the embodiment shown in FIGS. 1–7, those portions of the confectionary product container shown in phantom are not part of the design sought to be patented and are provided for environmental purposes only;

FIG. 9 is a top plan view of the second embodiment of the container;

FIG. 10 is a bottom plan view of the second embodiment of the container;

FIG. 11 is a right side elevation view of the second embodiment of the container;

FIG. 12 is a left side elevation view of the second embodiment of the container;

FIG. 13 is a rear elevation view of the second embodiment of the container; and,

FIG. 14 is a perspective view of the second embodiment of the container.
